ART SHIELD

Application filed June 21, 1929. Serial No. 372,732.

The present invention contemplates the provision of a combined picture frame and plate upon which the picture is adapted to be painted, the entire article being formed from a single piece of material, which is substantially braced or reinforced and provided with means whereby the latter can be suspended or hung upon a wall.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views, and wherein:

20 Figure 1 is a front elevation of the article constituting the subject matter of the present invention.

Figure 2 is a sectional view on line 2—2 of Figure 1.

25 Figure 3 is a fragmentary rear elevation.

Figure 4 is a similar view of a modified form.

Before entering into a detail description of what is herein shown, I desire to have it understood that the combined picture frame and plate may be constructed from any suitable material and it may also vary in size and design without departing from the inventive idea. The article is formed from a single blank of material, preferably aluminum, and as illustrated in Figures 1 to 3 inclusive it is of substantially rectangular contour in plan, being formed with curved marginal edges 10, while the body portion 40 bounded by the curved edges 10 is substantially flat on one side, and it is upon this surface that the picture is painted. This surface is also slightly roughened as at 11 to facilitate painting of the picture, and to add to the effect of the latter. As shown in Figure 3 the rear of the body portion 11 is formed with vertically and transversely disposed ribs 12 and 13 respectively which materially strengthen and reinforce the frame 50 in its entirety, and one of the transverse ribs

terminates to provide eyes 14 by means of which the picture frame may be suspended upon a wall or the like.

In Figure 4 I have shown a picture frame of oval contour, but otherwise the frame is exactly the same as hereinabove described, the rear or body portion being formed with transverse and vertically disposed ribs 16 and 17 respectively, with one of the transverse ribs terminating to provide eyes 18 for the purpose above mentioned.

While it is believed that from the foregoing description the nature and advantages of the invention will be readily apparent, I desire to have it known that I do not limit myself to what is herein illustrated and described, and that such changes may be resorted to when desired as fall within the scope of what is claimed.

What I claim:

As a new and improved article of manufacture, a combined picture frame and plate upon which a picture is adapted to be painted, said article being formed from a single piece of material and including a substantially flat body portion, and offset marginal edges of artistic cross sectional contour, vertical and transverse intersecting ribs formed on one side of the body portion, and eyes formed on the terminals of one of said transverse ribs for the purpose specified.

In testimony whereof I affix my signature.

GEORGE G. SINGER, JR.
